UNITED STATES PATENT OFFICE

MILTON L. DODGE AND HUGH A. JORDAN, OF NEWBURYPORT, MASSACHUSETTS, SAID
JORDAN ASSIGNOR TO SAID DODGE

METHOD OF MAKING SHOES

Application filed January 27, 1930. Serial No. 423,657.

This invention relates to the manufacture of shoes, more particularly turns, and has for its chief object the production of high grade shoes in a simple and economical manner. When applied to turn shoes it eliminates the necessity of hand work in the shaping of the soles and produces results superior to those obtainable where hand work is used.

While certain aspects of the invention are not limited to the manufacture of turns, the invention will be described with particular reference thereto due to its particular utility in such manufacture.

In general the method as applied to turn shoes is as follows. The shoe is lasted wrong side out while the shoe is in temper, in the usual manner, the last is drawn and the shoe turned. Then the forepart and shank at least of the sole are molded under pressure with or without a shank stiffener as in the manner disclosed in the Dodge Patents No. 1,537,419, granted May 12, 1925, or No. 1,707,656, granted April 2, 1929, respectively. Preferably, also, toe and counter stiffeners are also incorporated in the shoe at any suitable stage in the process and the toe and heel may be shaped over forms, as is shown in the Dodge Patent No. 1,701,997, granted February 12, 1929, and Dodge application Serial No. 296,576, filed July 31, 1928, both for method of making turn shoes. As will be hereafter pointed out the shaping of the toe portion over a form is advantageous in advance of the relasting of the shoes, and this operation, as also the heel forming, when this is done, may be performed either before or after the molding of the sole, as may be desired.

Instead of permitting the sole to dry out after the sole molding operation, as described in the Dodge Patents No. 1,537,419, and No. 1,707,656, and applications for patents hereinbefore identified, in accordance with the present invention, the toe portion of the shoe is preferably shaped over a form as described in the Dodge application for patent, Serial No. 694,136, and the shoe is relasted while the sole is still somewhat in temper, and while on the last, the shank, and if desired also, the forepart portions of the sole are sub-

jected to molding pressure and preferably there held for a suitable time. While any suitable molding mechanism may be used, the best results have been obtained by the use of a special, somewhat resilient, molding form, 55 which exercises an initial wiping action from about the break line of the sole rearwardly when pressure is applied thereby to the sole, and this form is well adapted for use, although not limited thereto, in a machine of 60 the type shown in our application for patent, Serial No. 142,317 filed by us October 18, 1926, for molding machines, which shows a molding machine in which the molding pressure may be exerted for a desired length of time 65 without interfering with the normal operation of the machine.

This application is a continuation in part of our application Serial No. 301,628, filed August 23, 1928, for method of making shoes. 70

For a more complete understanding of this invention, reference may be had to the accompanying drawings in which

Figures 1 and 2 are side elevations of a shoe assembled and having its toe portion 75 turned respectively.

Figures 3 and 4 are detail sections illustrating the toe forming operation.

Figures 5 and 6 are side elevation and bottom plan views respectively, of the shoe after 80 the toe forming operation.

Figure 7 is a view partly in section showing the sole molding operation.

Figure 8 is a bottom plan of the shoe after 85 the sole has been molded.

Figures 9 and 10 are a side elevation and an inverted plan view, respectively, of a form specifically designed for use in the second molding operation.

Figure 11 is a section on line 11-11 of 90 Figure 9.

Figure 12 is a fragmentary side elevation of a molding machine using the form shown in Figures 10, 11, and 12.

Referring to the drawings, Figure 1 shows 95 the upper 1 positioned wrong side out on a last 1 preparatory to the lasting operation. The shoe is lasted with the sole in temper, the last is then drawn and the shoe is turned.

As the toe is turned it is possible to incor- 100

porate a toe stiffener therein, as is disclosed in the Dodge Patent No. 1,453,925, granted May 1, 1923, this being shown in dotted lines at 3 in Figure 2.

- 5 Before turning the heel portion of the shoe, a combined counter stiffener 4 and shank piece 5 may be placed in position on the heel end face of the sole (Figure 2) after which the heel may be turned thereover and the 10 lining tucked down onto the rear portion of the shank piece, as at 6, and the flap 7 may then be folded back in position thereover. The toe portion of the shoe may then be drawn over a form 8, which is turnable on 15 its axis 9 relative to a stand 10 by which it is supported. The upper 11 may be presented upwardly as shown in Figure 3, so that the workman may readily smooth it down to the form, and it may be reversed to 20 present the sole upwardly as shown in Figure 4, so that the sole 12 at the forepart may be pounded down and the inseam flattened. In some cases it may be desired to heat the form as by a heating unit 14. When a toe stiffener 25 containing a stiffening agent softened by a solvent is used this aids in driving off the solvent so as to harden the stiffener. When a toe stiffener containing a thermoplastic stiffening agent is used it softens the stiffener 30 so that it can more readily be shaped to the form, and its marginal portion more thoroughly flattened at the inseam.

- Either after removing from this form or before application to this form, as may be preferred, the entire forepart and shank portion of the sole is molded between metal forms 14 and 15 of Figure 7. This is done while the sole is still somewhat in temper, and more or less distorted depending partly 40 on whether or not the toe shaping has been previously effected on the toe form.

The shoe is then subjected to the usual relasting operation but before the sole has dried out so that it is still somewhat in temper.

- The shaping of the toe portion of the shoe on the form facilitates the insertion of the toe of the relasting last so that the relasting operation is greatly facilitated. It also 50 causes the toe portion of the relasting last to bear on an extended area of the toe portion of the shoe, which effectively prevents the last from pushing forwardly of the sole, or "overshooting" which is a common difficulty in the relasting of shoes directly after the turning operation as heretofore practiced, and which requires additional operations in order to set the sole forwardly on the relasting last. This is often imperfectly done so 60 that the shoes are not uniform in the relation of the upper to the sole, thus detracting materially from their appearance when associated in pairs.

The shoe is then subjected to a second sole molding operation on the relasting last, the

length of time to thoroughly set the sole to the last. A time interval of two or three minutes at least is highly desirable for this second molding operation since there is then little if any tendency for the sole to spring out from its molded condition when the pressure has been released as has been found the case where pressure is applied either by hammers or by pounding out machines as heretofore constructed where the pressure has been applied by a series of blows.

A molding form particularly suitable to use in this second molding operation and claimed in our application, Serial No. 398,654, filed Oct. 10, 1929, for sole molding mechanism is illustrated in Figures 9 to 11, and is shown in use on a molding machine in Figure 12. Referring to these figures, it will be seen that the form comprises a support 20 which is provided on its upper face with any suitable means by which it may be fixed to a platten of a molding machine. As shown for this purpose there is provided a dovetail bar 21 fixed to the support 20 by any suitable means such as screws 23. One end of this bar is shown as provided with an upstanding lug 24 through which is threaded an adjusting abutment screw 25. When this form is applied to the molding machine shown in Figure 12, the bar fits in a mating groove in the platten 27 and this abutment screw 25 engages a shoulder portion 26 on the platten and limits the rearward and downward motion of the form relative thereto. As shown the form carries a pair of molding elements as 30 and 31. The molding element 30 is shaped to mold the shank portion of the shoe and may be used alone if desired, although it is usually preferable to mold the forepart by the same molding operation, in which case the element 31 will be used. Each of these elements 30 and 31, or more especially the element 30 comprises a plate of resilient material such as spring steel as shown best at 35 in Figure 11, this plate being overlaid with a suitable cushion, such as 36, of sole leather or the like, shaped more accurately to the contour of that portion of the shoe which is to be engaged by the element. In the shank form this cushion 36 is shown as having a central re-entrant portion 370 which is preferably somewhat more acute than the corresponding portion of the shank in order that molding pressure may be exerted more particularly on the side margins of the shank to force them down to the wood of the last.

The element 30 is carried by the support 20 by means which permit it to have a limited motion toward and from this support. For this purpose a strap 37 is shown as fixed to the rear or top face of the plate 35, its ends being upwardly turned as at 38 to receive screws 39 which form pivots for the

lower ends of a pair of links 40, the upper ends of which are hinged at 41 to one end portion of the support 20. Interposed between the element 30 and the support 20 are 5 springs 42 which preferably have their upper ends fixed to the lower face of the support as by screws 43. The element 30 is thus permitted a resilient motion toward and from the support 20 being guided in 10 this motion by the links 40. It will be noted that this form is concave on its under face, the concavity being particularly pronounced toward its forward end and within the concavity rides the rearward end of the forepart molding element 31. This element is provided toward its forward end with a transverse strap 48 having upturned ends 49 to which are pivoted links 50 pivoted at their opposite ends to the side of the support 20, as at 51. The upturned ends 49 are also connected through pivoted links 52 and 53 with the forward portion of the support 20, as at 54. Interposed between the element 31 and the support 20 are the coil springs 55 which 20 are preferably fixed to the under side of the support 20 as by screws in the manner previously described for the springs 42. The forming plates, particularly the shank forming plate 30, being of spring material yields 25 when forced under pressure against the outside face of the sole, exerting its pressure very strongly against the marginal portions of the shank so as to seat them firmly to the last, and, being of resilient or spring material, this pad is enabled to conform under 30 heavy pressure to the contour of the last so that the same form can be used for a considerable range of sizes and shapes of lasts. Moreover, as the elements are brought down 35 onto the shoe, this shank form exerts a downwardly and rearward wiping action on the shank until it is firmly seated in pressure contact therewith. This initial wiping action serving to smooth down the sides of the 40 shank portion of the sole acts to help in forming the sole to the last contour. Since the forepart is substantially flat the same wiping action is of less importance at this portion of the shoe, although it takes place 45 to some extent.

In order that the form may be held in molding contact with the shoe for a substantial period, some type of machine which will permit this without substantially slowing down the rate of progress of the shoes through the factory is of importance, and such a machine is shown in our Patent No. 1,709,842, granted Apr. 23, 1929. A portion of the top of this machine, as slightly modified for the purpose of this molding operation, is shown in Figure 12. Referring to this figure, it will be seen that on the machine bed 60 is fixed a block 61 within which is journaled a rod 62 having opposite end portions 63 and 64 threaded oppositely. The

threaded portion 63 is in threaded engagement with a toe support 65 of any suitable description and the rear threaded portion 64 is in similar engagement with a last pin supporting post 66. These supports for the shoe may be 70 adjusted from and toward each other by turning the shaft 62 as by means of the handle 68. The molding form is fixed to the platten 27 as hereinbefore suggested and this platten having fixed thereto on opposite sides 75 an actuating bar 70. This bar 70 is fixed to an arm 71 to which is also fixed an arm 72, which is connected to the rear portion of the platten 27. The arm 72 and the link 71 are fixed to a shaft 73 which is vertically slidable between jaws 74 of a bracket 75 made fast to the machine frame. Normally this shaft 73 is held at the upper portion to the bracket 70 as by means of the leaf spring 76. An actuating rod 77 is fixed at its upper end, as at 78, to the actuating bar 70 and the link 71, and when it is depressed, its first action is to turn the bar 70, link 71, arm 72 and the platten 27 to a position directly over the shoe supported on the posts 65 and 66, 80 whereupon further downward pressure exerted thereon brings the shaft 73 downwardly and applies the sole engaging elements 30 and 31 directly to the sole of the shoe. In accordance with the showing of our joint 85 patent hereinbefore identified the work table 60 may then be swung around while the shoe is held under sole molding pressure and while others are being inserted or removed, and the sole molding pressure is then released so 90 that a shoe which is molded may be taken out from the machine and a shoe to be molded inserted therein, while other shoes are held under molding pressure. It is found that by exerting the molding pressure in this 95 manner, no hand pounding out of the sole is necessary during the entire manufacture of the shoe, and that a very much better molded contour can be produced than by the hand method of pounding out or by machines 100 which exert a pounding action in shaping 105 the sole.

After this second molding operation the progress of the shoe through the factory may follow any usual or suitable order, the succeeding operations forming no part of the present invention.

An improved method by which this invention may be carried out and mechanism particularly designed to carry out this method having thus been described, it should be evident to those skilled in the art that various changes and modifications may be made therein without departing from the spirit or scope of this invention as defined by the appended claims.

We claim:

1. The step in the manufacture of a turn shoe which comprises wiping rearwardly from the forepart the shank portion of the

sole while the shoe is on the relasting last and holding the shank portion under molding pressure in such wiped condition for a substantial period.

- 5 2. The method which comprises lasting a shoe wrong side out on a last with the sole in temper, withdrawing the last, shaping the toe portion and molding the sole, relasting while the sole is still somewhat in temper, 10 molding the shank portion of the sole to the last, and then completing the shoe.
- 15 3. The method which comprises lasting a shoe wrong side out on a last with the sole in temper, withdrawing the last, shaping the toe portion and molding the sole, relasting while the sole is still somewhat in temper, 20 molding the shank and forepart portions of the sole to the last, and then completing the shoe.
- 25 4. The method which comprises lasting a shoe with the sole in temper wrong side out on a last, withdrawing the last, turning the shoe, shaping the toe portion of the shoe, relasting the shoe while the sole is still in temper, 30 molding the shank portion of the sole to the relasting last, and completing the shoe.
- 35 5. The method which comprises lasting a shoe wrong side out on a last, withdrawing the last, turning the shoe, shaping the toe portion, relasting, molding the shank portion of the sole to the last, and then completing the shoe.

In testimony whereof we have affixed our signatures.
